UNITED STATES PATENT OFFICE.

DANIEL JOSEPH EGAN, OF PICHER, OKLAHOMA.

GAS-ENGINE HEAD.

Application filed September 10, 1924. Serial No. 737,016.

To all whom it may concern:

Be it known that I, DANIEL JOSEPH EGAN, a citizen of the United States, residing at Picher, in the county of Ottawa and State of Oklahoma, have invented certain new and useful Improvements in Gas-Engine Heads, of which the following is a specification.

The present invention relates to internal combustion engines, and more particularly to the head construction.

An object of this invention is to provide a detachable head which is of the type adapted for use on the internal combustion engine known as the Bessemer engine, and which is an improvement upon the various heads which have heretofore been designed and used for this type of engine.

Another object of the invention is to provide a head which may be made in two pieces and constructed of steel and which is also provided with a water jacket of ample proportions.

Another object of the invention is to provide a two piece steel head which permits of easy access to the interior of the water jacket, which is provided with relatively large spaces for water circulation, and which is equipped with attaching bolts and housings therefor to protect the bolts from direct contact with the water in the jacket.

Another object of the present invention is to provide a head with a pair of cupped shaped sections one larger than the other and which are arranged to interfit with a space therebetween for water and which are interconnected by tubes or pipes which register with openings through said sections for receiving bolts for fastening the head in place and which protect the bolts from direct contact with the water in the jacket.

A still further object of the invention is to provide the head with a removable plate or cover which forms a wall of the water jacket and which may be easily and quickly removed independently of the head to gain access to the interior of the water jacket without disturbing the seating of the head on the cylinder.

The above and various other objects and advantages of this invention will in part be described in and in part be understood from the following detailed description of the present preferred embodiment, the same

being illustrated in the accompanying drawings, wherein:

Figure 1 is an outer plan view of the head.

Fig. 2 is a fragmentary longitudinal section through the head and adjacent part of a cylinder taken substantially on the line 2—2 of Figure 1.

Fig. 3 is a transverse section through the head taken on the line 3—3 of Figure 2.

Fig. 4 is a longitudinal section similar view of the head like Fig. 2 but taken substantially on the line 4—4 of Figure 1.

Fig. 5 is a longitudinal section taken through the outer section of the head.

Fig. 6 is a similar view of the inner section of the head.

Referring to the drawings 10 designates a cylinder of any suitable construction which is open at its top and provided in its side wall with a jacket 11 for water or other cooling medium.

The head of this invention is preferably made of a pair of pressed steel sections 12 and 13 which are bolted in superposed relation upon the open end of the cylinder 10. These sections 12 and 13 are both cupped shaped and are pressed from sheet steel to provide heads which are not liable to crack under conditions which invariably crack and destroy cast iron heads.

The inner section 13 is pressed into substantially dome shape to form an interior diameter equal to that of the cylinder 10 and provide a continuation of the cylinder. The section 13 has an outturned annular flange 14 of a width equal substantially to the thickness of the wall of the cylinder 10 and which has a plurality of openings 15 which communicate with the water jacket 11 of the cylinder. This flange 14 is provided with an alternate row of threaded openings which are interposed the openings or slots 15 and which are adapted to receive the externally threaded ends of tubes or pipes 16 which are arranged in a circular row upon the flange 14 and about the dome shaped section 13.

These tubes 16 terminate a short distance beyond the end of the section 13 to determine the thickness of the water jacket in the head.

The outer section 12 of the head is pressed into substantially cylindrical form and is of a diameter sufficient to enclose the section 13

and also the tubes 16, the inner edge of the section 12 resting upon the outer edge portion of the flange 14. The tubes 16 extend outwardly through the section 12 and 5 through openings 17 formed in the outer end of the section. The outer end of the section is constructed of an inwardly extending flange 18 pressed from the steel body of the section 12 and which is relatively shallow to 10 provide a large opening in the outer end of the section 12. The section 12 has welded or otherwise suitably secured thereto an attaching ring or plate 19 which is secured against the outer side of the flange 18 and 15 which preferably extends inwardly beyond the same to afford ample purchase for a plurality of bolts 20 which may be screwed into the ring 19.

The section 12 has a relatively large opening 20 through its outer end to admit easy access to the interior of the head, or the space between the sections 12 and 13. The ring 19 is preferably welded to the flange 18 and the openings 17 pass through the flange 18 25 sufficiently to permit the tubes 16 to pass entirely through the outer section 12 so that the outer section may be firmly seated upon the flange 14.

The assembled heads are adapted to be 30 secured upon their cylinders 10 by machine screws or bolts 21 which may be of suitable form and which may in the present instance comprise bolts which fit snugly in the tubes 16 and which are threaded on opposite ends, 35 one end of each bolt being threaded in the wall of the cylinder 10 while the other ends of the bolts 21 project beyond the tubes 16 and through the outer section 12 of the head for receiving clamping nuts 22 which 40 are adapted to bind against the outer surface of the ring 19.

There are preferably 12 of these bolts 21 and a like number of tubes 16 for receiving the bolts and for housing the same from contact with the water in the jacket between the 45 sections 12 and 13.

Access to the water jacket in the head is had through the opening in the middle of the ring 19, and this opening may be closed 50 by a cover plate 23 of a size adapted to fit within the circular row of bolts 21 and which is held securely over the ring 19 by the machine screws 20. The spark plug 24 is threaded in a cage 25 which is suitably secured in the top of the dome section 13 and which is of sufficient depth to extend to the inner side of the cover plate 23, and is provided thereat with an outturned flange 26 carrying threaded bolts 27 which project 55 through the cover plate 23 and receive clamping nuts 28 thereon for binding against the plate 23 to seal the plate about the cage 25. The cover plate is preferably apertured to register with the pocket in the 60 cage so as to permit free access to the spark 65

plug 24 and to accommodate the same. It is thus seen that a head is provided which may be made of pressed steel to the desired configuration and which may be tightly clamped into place without danger of breakage and which will not readily crack. The head is also economically constructed from sheet steel and is provided with a spacious water jacket adapted to contain a relatively large amount of water and to admit of a free and unobstructed circulation of the water. The clamping bolts are protected from contact with the water and consequently corrosion and deterioration of the bolts cannot take place. The clamping bolts 70 21 not only secure the head upon the cylinder 10, but also clamp the two sections 12 and 13 one upon the other and bind the flange 14 against the end of the cylinder 10. The flange 14 is therefore bound between the 75 cylinder 10 and the outer section 12.

Access may be readily had to the interior of the water jacket for cleaning out the same by the removal of the cover plate 23 so that the interior of the head may be left unobstructed and maintained clear at all times.

The above and various other detailed construction may be resorted to in carrying out the spirit of this invention without departing therefrom and the changes and modifications are restricted only by the scope of the following claims.

I claim:

1. A cylinder head comprising an inner dome shaped section having an outstanding annular flange having openings formed therein, a spark plug receiving cup secured in the head of the inner section and having a spark plug receiving opening, a section forming an outer facing, having an annular wall engaging said flange and enclosing the openings formed therein and an inwardly extending flange having opening aligned with certain of the openings formed in the flange of the inner section, tubes between the inner and outer sections having their ends secured in the aligned openings and adapted to receive fastener bolts for securing the cylinder head to a cylinder, a disc carried by the inwardly extending flange of the outer section and extending inwardly beyond the same and provided with a central opening, said disc provided with openings registering with the openings in the flange of the outer section, and a cover plate secured to the outer face of said disc and to the outer end portion of the spark plug receiving cup and having an opening registering with the interior of said plug receiving cup.

2. The combination with a cylinder and a water jacket about the cylinder, of a cylinder head comprising an inner dome shaped section having a head and a wall of an internal diameter corresponding to the internal diameter of the cylinder wall and an out-

standing flange engaging the ends of the cylinder wall and water jacket and having openings between the cylinder wall and water jacket, an outer section having an annular wall engaging said flange and enclosing the openings therein and an inwardly extending annular head forming flange provided with openings aligned with certain of the openings in the flanges of the inner section, tubes between the inner and outer cylinders having their ends secured in the

aligned openings of the inner and outer sections, fastener bolts carried by said cylinder and extending through said tubes and having securing nuts upon their outer ends, a closure plate secured to the flange of the outer section and having an opening, and a spark plug receiving cup secured in the head of the inner section and secured to the closure plate about the opening therein. 15

DANIEL JOSEPH EGAN.
